ABSTRACT: A hollow storage receptacle including a lower gravity flow outlet having inlet and outlet ends. A powered fluid pump is operatively associated with the receptacle and includes a fluid inlet, other than the gravity flow outlet, for intaking fluid from within the receptacle and a fluid outlet nozzle. The outlet end of the outlet nozzle is of smaller diameter than, aligned with and positioned adjacent the inlet end of the gravity flow outlet for discharging a jet of fluid into said outlet in the manner of an eductor.

APPARATUS FOR EMPTYING LIQUID TANKS

This invention relates to a novel means of rapidly emptying liquids from tanks when the liquid is of a nature to be pumped under pressure.

The invention lends itself most favorably to tanker units of rural fire departments, where the ability to unload the water swiftly from the tank of the tanker into a suitable reservoir such as a portable tank, is a great asset in many instances. Most rural fire department tanker units are provided with pumps which may be used to pump a stream of water on a fire and also a large gravity flow outlet from which the tanker may be emptied into a portable tank such as that disclosed in U.S. Pat. No. 2,749,956. While some tankers include pumps and some tankers may not include pumps, when a portable tank is utilized at a fire location remote from a supply of water the tanker has its water drained or pumped therefrom into the portable tank from which the pumpers at the fire scene may pump water onto the fire. As soon as the tanker has emptied its tanks into the portable tank, it is free to travel the necessary distance to a suitable supply of water and be refilled with water and then return to the scene of the fire, possibly before the pumpers at the scene of the fire have exhausted the supply of water in the portable tank. However, it can be appreciated that the time required to empty the tanker into the portable tank must be kept at a minimum in order to allow the tanker the maximum length of time to travel to a suitable supply of water, refill and then return to the scene of the fire before the pumpers at the fire scene have emptied the portable tank.

A 1,000 gallon tanker is capable of discharging its full supply of water into a portable tank through a 4½ inches outlet in approximately 5 minutes. With the apparatus of the instant invention in operation the same 1,000 gallon tanker can discharge its load of water in approximately 55 seconds thereby affording at least an additional 4 minutes time for the tanker to travel to a suitable source of water, be refilled and then return to the fire scene. Thus it can be appreciated how beneficial the apparatus of the instant invention can be in fighting fires in rural communities. In order for a 1,000 gallon tanker to be emptied in approximately 55 seconds it is necessary that it be provided with a pump of suitable capacity having approximately a 2½ inches suction line, a 2 inch pump discharge line, a 1½ inch ejector nozzle and a 4½ inch tank dump line with the ejector nozzle pressure being approximately 50 pounds per square inch and discharging 265 gallons per minute from the pump.

The main object of this invention is to provide a rapid dump system for tanker trucks. Another object of this invention is to provide a rapid dump system which may be readily incorporated into the construction of various fire fighting tanker trucks.

Still another object of this invention is to provide a rapid dump system which may be readily practiced in other environments.

A final object of this invention to be specifically enumerated herein is to provide a rapid dump system in accordance with the preceding objects which will conform to conventional forms of manufacture, be of simple construction and easy to use so as to provide a device that will be economically feasible, long lasting and relatively trouble-free in operation.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIG. 1 is a side schematic view of a tanker unit;

FIG. 2 is a fragmentary side elevational view of the tank portion of the tanker unit with portions thereof being broken away and illustrated in longitudinal vertical section; and

FIG. 3 is an enlarged transverse vertical sectional view taken substantially upon the plane indicated by the section line 3-3 of FIG. 2.

Referring now more specifically to the drawings, the numeral 10 generally designates a conventional form of tanker truck which has been modified in accordance with the present invention. The truck 10 includes the usual cab 12 and body 14. In addition, the tanker 10 includes a tank construction referred to in general by the reference numeral 16 including top and bottom walls 18 and 20, opposite sidewalls 22 and 24 and opposite end walls 26 and 28.

The tank 16 includes a longitudinal upstanding center partition 30 and longitudinally spaced upstanding transverse partitions 32. The upper and lower corners of the transverse partitions 32 are cut away as at 34 and the longitudinal partition 30 is cut away in a similar manner as at 36 adjacent each transverse partition 32 and the opposite end walls 26 and 28.

The preceding description of the tank 16 may be considered as conventional except that the cutaway portions 34 and 36 are larger than usual in order to allow more rapid flow of water from each area within the tank 16.

A further modification of the tank 16 in accordance with the present invention is that the bottom wall 20 thereof is provided with a central longitudinally extending trough 38 including opposite sidewalls 40 and a bottom wall 42. In addition, a large 4½ inch diameter tank dump line 44 opening rearwardly through the rear end wall 26 is provided and includes an outlet end 46 disposed rearwardly of the tank 16 which is valved as at 48. In addition, the forward end of the tank 16 includes a sump generally referred to by the reference numeral 50 and the tanker 10 is provided with a pump assembly 52 which may be driven either by a power takeoff of the tanker 10 or by an auxiliary power supply (not shown). The pump 52 includes a 2½ inch suction line 54 which is valved as at 56 and whose inlet end opens into the bottom of the sump 50. The outlet end of the suction line 54 opens into the pump casing 58 as at 60 and the pump casing 58 includes a 2 inch discharge line 62 which is valved as at 64 and opens into the interior of the tank 12 through the front wall 28 thereof and extends along the forward end of the trough 38 and has an eductor nozzle 66 on its outlet end aligned with and spaced slightly outwardly of the inlet end of the 4½ inch tank dump line 44. In operation, when it is desired to empty the tank 16 into a portable tank such as that disclosed in U.S. Pat. No. 2,749,956, the pump 52 is actuated whereby water is pumped through the eductor nozzle 66 at approximately 50 pounds per square inch and at a rate of 265 gallons per minute from the pump 52. This discharge of water from the nozzle 66 reduces the pressure of water in the inlet end of the tank dump line 44 and accelerates the flow of water therethrough whereby the entire 1,000 gallons within the tank 16 may be emptied therefrom in approximately 55 seconds, as opposed to approximately 5 minutes if the eductor nozzle 66 and pump 52 were not used.

Although the tank dump system of the instant invention has been specifically illustrated and described herein as being a part of a tanker truck, it is to be noted that it could be readily utilized for rapidly emptying various tanks containing various fluids. Furthermore, a compound eductor nozzle could be utilized in lieu of nozzle 66.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention.

I claim:

1. In combination, a fluid storage tank having a lower gravity flow outlet including inlet and outlet ends, a powered fluid pump operatively associated with said tank and including a fluid inlet, other than said outlet, for intaking fluid from within said tank and a fluid outlet nozzle of smaller diameter than said inlet end with its outlet end aligned with, adjacent and opening outwardly toward said inlet end.
2. The combination of claim 1 wherein said fluid storage tank is supported upon a wheeled vehicle.
3. The combination of claim 2 wherein said wheeled vehicle 75 comprises a tanker-type fire engine.

4. The combination of claim 1 wherein said tank includes a bottom wall and an upstanding sidewall, said bottom wall defining an upwardly opening trough extending therealong toward said sidewall, said gravity flow outlet including a large diameter pipe disposed in said trough with its outlet end opening outwardly through said sidewall, said outlet nozzle being disposed in said trough.

5. The combination of claim 4 wherein said fluid storage tank and pump are supported from a tanker-type fire engine chassis.

6. The combination of claim 1 wherein said tank includes internal baffle means provided with sufficient void areas to enable rapid but controlled movement from one area of said

tank to another area.

7. In combination, a fluid storage tank having a lower gravity flow outlet including inlet and outlet ends, a powered fluid pump operatively associated with said tank and including a fluid inlet, other than said outlet, for intaking fluid from within said tank and a fluid outlet, said fluid outlet including eductor nozzle means operatively associated with said gravity flow outlet for accelerating the fluid flow therethrough in response to operation of said pump means.

10 8. The combination of claim 7 wherein said fluid storage tank and pump are supported from a tanker-type fire engine chassis.
